UNITED STATES PATENT OFFICE.

SETH KIRK, OF ABILENE, TEXAS.

RUBBER-EXTRACTING MACHINE.

No. 988,714.

Specification of Letters Patent.

Patented May 26, 1908.

Application filed March 7, 1907. Serial No. 361,155.

To all whom it may concern:

Be it known that I, SETH KIRK, a citizen of the United States, residing at Abilene, in the county of Taylor and State of Texas, have invented certain new and useful Improvements in Rubber-Extracting Machines, and do declare that the following is a full, clear, and exact description of the invention, which will enable others skilled in the art to which it appertains to make and use the same.

My invention relates to improvements in rubber extracting machines, and the improvement consists in the construction and combination of parts, substantially as hereinafter shown and described and more particularly pointed out in the claims.

The object of the invention is to extract rubber from caoutchouc roots and plants, such as the *Guayule* plant, by mechanical means and with the agency of steam and water. The first step, however, is to cut the material into short lengths and then crush the same and convey it in the form of a warm wet pulp to the fiber removing and rubber forming machines which comprise this invention. An assembly of such machines is required for complete and satisfactory working of the material and I therefore, prefer to use a set of three machines of different sizes, the smaller of which provides for the preliminary extraction and working together of the rubber, and the larger of which is used as a finishing machine to work over the product of the first machines and bring all the extracted rubber together. Said machines are suitably arranged in respect to each other and provided with means to convey the material from the first machine to the last and thence to a final discharge place where it may be gathered for final washing and refining.

In the accompanying drawings, Figure 1 is a plan view of a set of three of my improved machines, and Fig. 2 is a side elevation thereof showing the main frame and various other parts in section. Fig. 3 is a plan view of one of the upper machines showing the top plate member broken away in part to disclose the fluted formation of the lower rotary member. Fig. 4 is a sectional view on line 4-4, Fig. 3, and Fig. 5 is a cross section of a portion of two machine plates showing the working relation between their rolling and crushing ribs or fluted faces.

Referring to the drawings, the numeral --2-- represents a pair of similarly con-

structed machines arranged side by side above a somewhat larger and substantially like machine --3-- which is located centrally between the first named two, and all three 69 machines are supported in common upon a suitable frame --4--.

Each machine comprises a pair of disk shaped plates or members 5 and 6, respectively, cast of metal and mounted one upon 65 the other with fluted meeting faces providing ribbed portions 7 and 8, respectively. The flutes and ribs on lower plate --5-- are disposed tangentially over its upper face and the flutes are of gradually increasing width 70 from their beginning at substantially the center of the plate to where they terminate in the plate itself at a shoulder or edge formed by an annular recess --9-- at the outer half of the plate. Recess 9 is filled with wood 10 75 faced off flush with the face portion of said plate and is also fluted and ribbed to within a few inches of its outer edge to correspond to fluted portion 7 and as a continuation thereof. It will also be noted that said 80 flutes or grooves are of gradually increasing depth from the center outwards. Upper plate 6 is similarly fluted and ribbed over its central portion and recessed at its outer portion and filled with wood to match with the 85 lower plate but the flutes therein are radially disposed as seen in dotted lines, Fig. 3 instead of tangentially as in the lower plate, although similarly increasing in width and depth from the center outward. In cross 90 section, said plate portions 7 and 8 have a tooth like formation as seen in Fig. 5, wherein the vertical faces thereof provide shoulders and cutting edges 12 which are opposed to each other in operation and whereby the material is cut and crushed and the rubber caused to roll, first over one tooth and then the next. The radial and tangential arrangement of the ribs and flutes provide for a shearing cut and outward feed of the material. 100 The feeding forward of the material and discharge of water and fiber is further facilitated by the downward inclination of the meeting faces of the two plates from the center thereof to the outer edge, the lower 105 plate having a slightly cone form and the upper plate flaring downward and outward to correspond.

The material is fed to each machine through a centrally arranged cylinder 14 110 mounted on plate 6 over an opening therein and a forced feed is provided by means of

screw 15 secured to lower plate 5 and which rotates with said plate. The inner face of cylinder 14 is grooved or ribbed vertically at an inclination to the vertical axis of screw 15 to promote feeding, and cutting and crushing of the material within the cylinder.

Wood is used for the ring like face 10 for each plate because it has better frictional qualities than metal and will provide the necessary pull at the finishing end of the plates to work the rubber outward and free. Each plate has two or more steam and hot water pipes 17 tapped into upper plates 6 at about the inner circular line of wood lined faces 10, and through which the requisite heat and moisture is supplied to the material being treated.

Upper plate 6 is fixed against rotation but is adapted to rise and fall in respect to lower plate 5 as the material is crushed and the rubber forms in rolls of varying diameter between them. Thus, machines 2 have vertical screw stems 18 secured to the top of plate 6 by suitable caps 19, and brackets 20 bolted to frame 4 have sliding engagement at their outer ends with said screws. Hand wheels 21 rest upon said brackets and are threaded upon said screw stems to raise the same and plate 6 to any suitable working height. Lower machine 3 being larger and its top plate 6 considerably heavier than those of the smaller machines, I prefer to use counterweighted connections 22 instead of screw connections 18, and whereby the weight of said plate may be controlled by adjustment of weights 23 on the free end of levers 24. Brackets 25 on frame 14 provide pivot supports for said lever. By removing weights 23 the full weight of plate 6 may be utilized.

Lower plate 5 of each machine is rotatably supported at its center by a gear 27 affixed thereto and which is mounted on a vertical shaft 26 resting in bearings on frame 4, and also by a series of rollers 28 mounted upon frame 4 beneath the plate near its periphery. Power is applied separately to each of the machines by means of separate pulleys 29,

bevel gearing and shafting 30, and vertical shafts 31 carrying pinions 32 which mesh with gears 27 on each bottom plate.

Each machine has a ring like trough 33 mounted upon frame 4 below the edge of lower rotatable plate 5, and each plate carries one or more arms having wiping blades 35 adapted to travel within said troughs and whereby the discharged material is carried around and dropped through an opening 36 in the bottom of the trough. The two upper machines empty their troughs directly into vertical hopper 37 leading to cylinder 10 of lower machine 3, and the trough of lower machine 3 has its opening 36 at one side where final discharge is made to any suitable receptacle adapted to receive it.

In operation, the wood fiber of the plant is crushed and cut by the machines and carried away by the water which is mixed with the material and fed to the machine, and the rubber being heated by the steam will work together between the plates and form into rolls of varying diameter and length before discharging into the troughs. These rolls of rubber vary from one-eighth of an inch to three inches in thickness when expelled by the larger machine.

What I claim is:

A rubber extracting machine comprising dual sets of rotatable and non - rotatable plates respectively constructed to crush and work the material into rolls, and means to set said plates in each set a predetermined distance apart, in combination with a single larger rubber extracting machine having rotatable and non-rotatable plates respectively for re - working the material and counterweighted mechanism for controlling the working relation between said plates, and means to convey the product of the first set of plates to the second set of plates.

In testimony whereof I sign this application in the presence of two witnesses.

SETH KIRK.

Witnesses:
